UNITED STATES PATENT OFFICE.

JOSEPH L. HERZOG, OF NEW YORK, N. Y.

DESIGN FOR AN ORNAMENTED STONE FOR JEWELRY.

SPECIFICATION forming part of Design No. 31,220, dated July 18, 1899.

Application filed June 16, 1899. Serial No. 720,856. Term of patent 14 years.

To all whom it may concern:

Be it known that I, JOSEPH L. HERZOG, of the city of New York, borough of Manhattan, in the county and State of New York, have

5 adopted a new and original Design for an Ornamented Stone for Jewelry, of which the following is a full, clear, and exact description.

The leading feature of my design consists of an elk's head produced upon a background 10 formed by the body of the stone.

As shown in the accompanying drawing, the elk is represented with the head turned

to one side, the antlers being curved toward each other and occupying the upper portion of the stone, the elk's eye being approximately in the center of the stone. 15

I claim—

The design for an ornamented stone for jewelry, herein shown and described.

JOSEPH L. HERZOG.
